[57] CLAIM

The ornamental design for a medic case, as shown and described.

DESCRIPTION

FIG. 1 is a perspective view of a medic case showing my new design;

FIG. 2 is a perspective view, showing the interior thereof;

FIG. 3 is a top plan view thereof, with the case in open position;

FIG. 4 is a left end elevational view thereof, showing the end shown in FIG. 2;

FIG. 5 is a front elevational view thereof, with the case in open position;

FIG. 6 is a rear elevational view thereof, with the case in open position;

FIG. 7 is a right end elevational view thereof, showing the end opposite that shown in FIG. 2;

FIG. 8 is a bottom plan view thereof, with the case in open position; and

FIG. 9 is a bottom plan view thereof.

FIG. 1.

FIG. 2.

FIG.3.

FIG.4.

FIG. 5.

FIG. 6.

FIG. 7

FIG. 8

FIG. 9
